(57) **CLAIM**

I claim the ornamental design for a food tray assembly, as shown and described.

DESCRIPTION

FIG. 1 is an elevated disassembled perspective view of the food tray assembly of my claimed design;

FIG. 2 is a top disassembled view of the food tray assembly of FIG. 1;

FIG. 3 is a bottom disassembled view of the food tray assembly of FIG. 1;

FIG. 4 is a left side disassembled view of the food tray assembly of FIG. 1;

FIG. 5 is a right side disassembled view of the food tray assembly of FIG. 1;

FIG. 6 is a front disassembled view of the food tray assembly of FIG. 1;

FIG. 7 is a back disassembled view of the food tray assembly of FIG. 1; and,

FIG. 8 is an elevated assembled perspective view of the food tray assembly of FIG. 1.

The broken lines showing a logo are for the purpose of illustrating environmental structure and form no part of the claimed design. In addition, the broken lines in FIG. 3 showing the elongated oval shapes in the first layer of trays, the series of short vertical lines around the interior edges of the second layer of trays, and the center area and the lines that extend from the center area in the second layer of trays also form no part of the claimed design.
